COMBINED SWORD AND REVOLVER

Filed March 19, 1923

INVENTOR
S. Kaperzenski

BY *Maxim Polking*
ATTORNEY

UNITED STATES PATENT OFFICE.

STANLEY KAPERZENSKI, OF DETROIT, MICHIGAN.

COMBINED SWORD AND REVOLVER.

Application filed March 19, 1923. Serial No. 626,181.

To all whom it may concern:

Be it known that I, STANLEY KAPERZENSKI, a citizen of Poland, residing at Detroit, in the county of Wayne and State of Michigan, have invented certain new and useful Improvements in Combined Swords and Revolvers, of which the following is a specification.

This invention relates to improvements in sabres, swords and the like, and has for its principal object to provide means for removably attaching a firearm thereto.

Another object of the invention is to provide means for attaching the firearm to the sabre without altering its construction in any way whatsoever.

Still another object of the invention resides in the provision of a device having a handle from which the blade may be detached for storage or transportation.

With these and other objects in view, the invention consists in the novel construction, combination and arrangement of parts hereafter described and shown in the accompanying drawing, in which:—

Figure 1 is a side view in elevation of my invention.

Figure 2 illustrates the device encased in a sheath.

Figure 3 is an enlarged detail, fragmentary side view of the device.

Figure 4 is an end view of Figure 3.

Figure 5 is an enlarged detail fragmentary sectional view through the device.

Figure 6 is an enlarged sectional view taken on line 6—6 of Figure 1.

Figure 7 is a perspective view of the clamp nut.

Referring to the drawings in detail, the numeral 10 designates in its entirety the handle of the device which comprises a grip 11 and guard 12. Extending longitudinally from one end of the grip is a socket member 13 provided in one longitudinal edge 5 with a groove 14.

Formed on the guard 12 is an extension 15 provided with a slot 16, the purpose of which will be more fully hereinafter set forth.

0 A blade 17 is provided adjacent its rear end with an arcuate portion 18, the innermost edge of which is provided with laterally extending flanges 19. The end of the arcuate portion, opposite that joining the blade, is provided with a tongue 20 adapted

to be received in the groove 14 previously described.

Formed at the joint of the outer edge of the blade with the arcuate portion is an undercut notch 21 constituting a forwardly 60 projecting tongue 22, the use of which will be more fully hereinafter described.

In order to secure the blade in the handle, an arcuate clamp 23 is provided to overlie the convex portion of the arcuate portion 65 18, and formed at the extreme forward end of said clamp is an inwardly extending arm 24 having a rearwardly extending finger 25 for engagement with the underside of the tongue 22. 70

Formed at the rear end of the clamp 23 is a rearwardly extending tongue 26, adapted to be received in the slot 16 previously described and a thumb screw 27 projects into the threaded opening 28 of the clamp nut 29. 75

This clamp nut comprises a substantially cylindrical body 30 formed with plates 31 on opposite sides and at the outer end with spaced parallel arms 32 formed with upwardly extending fingers 33. 80

Formed on the underside of the blade 17, near the arcuate portion 18, are a pair of flanges 34 forming a dove tail groove 35 for the reception of the upstanding rib 36 ordinarily formed on the upper side of the gun 85 barrel 37.

This gun comprises the usual barrel 37, cylinders 38, grip 39 and hammer 40, and connecting the grip with the barrel is the customary pivot 41 and latch 42. 90

A notch 43 is formed in the underside of the blade to accommodate the latch 42, so as to allow its free movement when opening and closing the gun frame.

In assembling the device, the tongue 20 95 of the arcuate portion 18 of the blade 17 is seated in the groove 14 in the socket 13, and the clamp 23 is then clamped in position by inserting the tongue 26 into the slot 16 and the arm 24 into the notch 21.

By turning the thumb screw 27 it will be seen that the arm 24 will be drawn rearwardly, bringing the finger 25 into the space below the tongue 22 and upon further turning the thumb screw, the whole will be 105 firmly clamped together.

The gun may be readily removed or replaced by sliding the rib 36 into and out of the dove tail groove 35 between the flanges 34. 110

While in the foregoing there has been shown and described the preferred embodiment of this invention, it is to be understood that minor changes in the details of construction, combination and arrangement of parts may be resorted to without departing from the spirit and scope of the invention as claimed.

Having thus described my invention, what I claim as new and desire to secure by Letters Patent, is:—

1. A device of the class described comprising a blade, a handle, a socket member on the handle, an arcuate extension on the rear end of the blade, a tongue adapted to seat in the socket member, arcuate plate clamping means, and a thumb screw co-operating with the handle and arcuate clamping means to hold the blade in place.
2. A device of the class described comprising a blade, a handle, a guard on the handle, a socket member on the handle, an arcuate extension on the rear end of the

blade, a tongue on the arcuate extension adapted to seat in the socket member, an arcuate clamp member, and means associated therewith projecting through the guard for clamping the whole together.

3. A device of the class described comprising a blade, a handle removably secured thereto, an arcuate extension at the rear end of the blade, a pistol, and means carried by the blade for securing the pistol to the blade adjacent the arcuate extension.

4. A device of the class described comprising a blade, a handle removably secured thereto, an arcuate extension on the blade adjacent the handle, flanges on the blade adjacent the concave portion of the arcuate extension, a pistol having a barrel, and a rib on the pistol barrel adapted to be received between the flanges.

In witness whereof I have signed my name to this specification.

STANLEY KAPERZENSKI.
